UNITED STATES PATENT OFFICE.

HENRY ACKERMAN, OF WEEHAWKEN, NEW JERSEY.

DESIGN FOR A JEWEL-MOUNTING.

44,328.

Specification for Design.

Patented July 15, 1913.

Application filed May 13, 1913. Serial No. 767,446. Term of patent 14 years.

To all whom it may concern:

Be it known that I, HENRY ACKERMAN, a citizen of the United States, residing in Weehawken, in the county of Hudson and State of New Jersey, have invented a new, original, and ornamental Design for Jewel-Mountings, of which the following is a specification, reference being had to the accompanying drawing, forming a part thereof.

Figure 1 is a plan view of a jewel mount-

ing showing my new design; and Fig. 2 is a side elevation of a jewel mounting showing my new design.

I claim:

The ornamental design for a jewel mounting as shown.

HENRY ACKERMAN.
